UNITED STATES PATENT OFFICE.

FRANK S. CROWELL, OF TOLEDO, OHIO, ASSIGNOR TO THE EDWARD N. RIDDLE CO., OF TOLEDO, OHIO, A CORPORATION OF OHIO.

DESIGN FOR AN ORNAMENTAL CANDELABRUM.

56,585.

Specification for Design.

Patented Nov. 16, 1920.

Application filed December 22, 1919. Serial No. 346,794. Term of patent 7 years.

To all whom it may concern:

Be it known that I FRANK S. CROWELL, a citizen of the United States, residing at Toledo, in the county of Lucas and State of Ohio, have invented a new, original, and ornamental Design for an Ornamental Candelabrum, of which the following is a specification, reference being had to the accompanying drawing, forming part thereof.

I claim:

The ornamental design for an ornamental candelabrum, as shown.

FRANK S. CROWELL.
